LEG PROTECTOR

Amanda Samille Woare, Devon, Mont.

Application June 14, 1938, Serial No. 213,698

1 Claim. (Cl. 36—2)

This invention relates to protectors for legs and stockings, and among other objects, aims to provide an improved protector which while neat in appearance, protects the legs against frostbite and moisture, and may be easily put on and taken off without removing the shoes and stockings and other articles of apparel.

A preferred embodiment of the invention is shown in the accompanying drawing forming a part of this specification. In said drawing—

Fig. 1 is a side elevation showing the protector open; and

Fig. 2 is a similar view but showing the protector applied to the leg.

Referring particularly to the drawing, there is shown a leg protector or "over hose" comprising a leg portion 5, of warm material as will be explained, a strap 6 to be passed under the arch portion of the shoe, and a lastex top 7 which may be just above or just below the knee, according to the preference of the user. On one side of the protector, a slide or "zipper" fastening 9 extends longitudinally from the extreme lower edge to a point about 8" or 10" above said lower edge, and the tab 10 is at the top of the fastening 9 when the protector is wide open. The protector may then be put on without removing the shoe, even if the shoe has high heels.

The leg portion 5 is preferably knitted double and fashioned like a stocking, with knitted wool on the outside, or a wool mixture "over thread", and an inner knitted lining or "under thread" of silk and cotton, silk and rayon, or rayon and cotton, so that no fuzz clings to the legs to mar the appearance of the stockings, and there is no irritation from the wool fibers. As is well known, women today wear sheer silk hose in all weather conditions and such hose would offer little protection against the harsh fibers which would project from the leg portion 5, if its undersurface were of wool. Preferably the leg por-

tion 5 is completely waterproofed. The lastex top may be narrower than shown, but should be sufficiently elastic to stretch to at least double, and preferably triple, its ordinary length. A great advantage of a lastex top is that it may be made on a machine at the same time the leg portion 5 is made. The strap 6 is preferably slightly elastic, to pass under the shoe and hold the protector snugly upon the instep. It may be sewed, riveted or stapled at its ends to the bottom edges of the protector. The protector may have a textile flap 11 at the inside of the slide fastening to protect the stocking against snags arising from use of the fastening.

It will be clear that the described leg protector makes it possible for a woman or girl to present her best appearance in fine silk hose at a party, at work or in school, and still be protected against chapped and frost bitten legs in cold weather or wet feet and legs in snowy or rainy weather. The protector cannot injure the sheerest hose, nor irritate the skin of the wearer, and it is so made as to be easily and quickly put on and removed without removing the shoes.

Obviously the present invention is not limited to the particular embodiment thereof herein described and shown.

What I claim as new and desire to secure by Letters Patent is:

A leg protector comprising a knitted leg portion extending approximately to the knee and having a wool or part wool outer layer and a non-wool inner layer of some soft textile material; a strap at the lower end to fit under the arch of the shoe; a lastex portion at the top of and integral with the leg portion; and a slide fastener on the outside extending longitudinally upwardly from the lower end for a fraction of the total length of the leg portion.
